CLAIM

The ornamental design for a housing for base of telephone, as shown and described.

DESCRIPTION

FIG. 1 is a top-front perspective view of the housing for base of telephone with a broken line showing of a handset in a cradled position showing my new design;
FIG. 2 is a front elevational view of the housing for base of telephone of FIG. 1;

FIG. 3 is a right side elevational view of the housing for base of telephone of FIG. 1;
FIG. 4 is a left side elevational view of the housing from base of telephone of FIG. 1;

FIG. 5 is a rear elevational view of the housing for base of telephone of FIG. 1; and,
FIG. 6 is a top plan view of the housing for base of telephone of FIG. 1.

The broken line showings throughout the views are for illustrative purposes only and forms no part of the claimed design.

FIG. 1**FIG. 2****FIG. 3**

FIG. 4

FIG. 5

FIG. 6
